UNITED STATES PATENT OFFICE.

GIORGIO MICHETTI, OF ROME, ITALY.

CINEMATOGRAPHIC APPARATUS.

Application filed October 3, 1921. Serial No. 504,983.

To all whom it may concern:

Be it known that I, GIORGIO MICHETTI, subject of the King of Italy, residing at 3 Lungotevere Castello, Rome, Italy, have invented a new and useful Improvement in Cinematographic Apparatus; and I do hereby declare the following to be a full, clear, and exact description of the same.

The invention relates to cinematographic apparatus and it has for its object to construct an apparatus of this type wherein the film is lodged inside the apparatus and the gearings are of such simple construction as to allow of the apparatus being reduced to a minimum size or of pocket formation.

The invention is illustrated by way of example in the accompanying drawings, in which—

Figure 1 is a front view of the apparatus with the cover removed,

Figure 2 shows the interior thereof and Figures 3, 4 and 5 are details of the apparatus.

The film travels round a toothed and apertured drum 1. The intermittent rotary motion of the drum is obtained by aid of a crank handle 2 and a gear wheel 3 through the intermediary of a gear wheel 4 and an escapement of the anchor type as usually employed in clocks. The gear wheel 3 engages a pinion on a shaft 5 for winding the film onto a spool and also with a pinion on a spindle 6 which has mounted on it a small eccentric 7 (Fig. 5) which causes a balance wheel 8 to oscillate so that teeth 9, 9' provided thereon strike alternately against teeth 10, 10' provided on an enlarged boss 11 (Figs. 3 and 4) at one end of the drum 1, thereby arresting the rotation of the drum for the required period of time at each exposure.

The gear 4 is mounted loose on the drum (Fig. 3) and is connected therewith through the only intermediary of a spiral spring 12 so that the necessary elasticity is obtained to compensate for the time during which the film remains at rest during exposure.

On the shaft 5 is mounted a bevel gear 13 which engages a bevel gear 14 mounted on a shaft, for example through a belt 17, to the shutter 16 of the apparatus.

a shaft 15, from which motion is trans-

The ratio of the various gears is such that shafts 5 and 6 complete six revolutions during each revolution of the gear wheel 3, 55 while the drum during this time completes one and a half revolutions, and each revolution of the crank handle therefore produces six exposures.

When turning the handle 2, the gear 3 produces a continuous motion of the various parts of the apparatus with the sole exception of the drum 1. This drum turns only during those intervals of time during which the eccentric 7 which alternately raises and lowers the balance wheel 8, disengages one of the teeth 10 of the boss 11 from the tooth 9 by which it was held up, so that the boss and the drum are able to complete a quarter revolution under the action of the gear 4 and of the spring 12. At the end of this rotation another tooth 10 will arrest the boss 11 by coming into contact with the second tooth 9' of the balance wheel.

Having now particularly described and ascertained the nature of my said invention and in what manner the same is to be performed, I declare that what I claim is:

1. In a cinematographic apparatus, a feed drum, actuating mechanism for the drum, a boss fixed to the drum, and a ring shaped balance member, cooperating with the boss, for regulating motion of the drum.

2. In a cinematographic apparatus according to claim 1, said balance member completely encircling said boss, and being pivoted at its periphery for oscillation, cooperating teeth on the boss and the balance member, and means positioned at the periphery of the balance member, for oscillating the member, whereby to afford a compact mechanism adapted for miniature apparatus.

In testimony whereof, I have signed my name to this specification in the presence of two subscribing witnesses.

GIORGIO MICHETTI.
